US00D854107S

(12) **United States Design Patent** (10) **Patent No.:** **US D854,107 S**
Choi (45) **Date of Patent:** **** Jul. 16, 2019**

(54) **TENT FRAME WITH CENTRAL UPRIGHT POLE AND EAVES**

(71) Applicant: **Campvalley (Xiamen) Co., Ltd.**,
Xiamen (CN)

(72) Inventor: **Kwan Jun Choi**, Xiamen (CN)

(73) Assignee: **Campvalley (Xiamen) Co., LTD.**,
Xiamen (CN)

(**) Term: **15 Years**

(21) Appl. No.: **29/600,929**

(22) Filed: **Apr. 17, 2017**

(30) **Foreign Application Priority Data**

Oct. 17, 2016 (CN) 2016 3 0505606

(51) **LOC (11) Cl.** **21-04**

(52) **U.S. Cl.**

USPC **D21/839; D21/834**

(58) **Field of Classification Search**

(57) **CLAIM**

The ornamental design for a tent frame with central upright pole and eaves, as shown and described.

DESCRIPTION

FIG. 1 is a perspective view of our new design of a tent frame with central upright pole and eaves;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines in the above described FIGS. 1-7 are for illustrative purposes only, depict environmental matter only, and form no part of the claimed design.

1 Claim, 7 Drawing Sheets
